MULTIPLE STAGE PROCESSING REEL

Filed Nov. 21, 1947

UNITED STATES PATENT OFFICE

2,609,589

MULTIPLE STAGE PROCESSING REEL

Albert W. Eidman, South Euclid, Ohio, assignor
to Industrial Rayon Corporation, Cleveland,
Ohio, a corporation of Delaware

Application November 21, 1947, Serial No. 787,368

4 Claims. (Cl. 28—71.7)

1

This invention relates to multiple stage thread storing, thread advancing reels upon which a thread or the like is stored and advanced in a plurality of generally helical turns. More particularly the invention relates to a reel adapted for a plurality of operations and capable of being made of any desirable length subject only to physical limitations.

Generally, reels constructed on the principle disclosed in the Knebusch Patent 2,210,914, have been advantageously utilized in the continuous manufacture of filamentary material such as rayon yarn, thread, etc. The reels comprise two reel elements rotating on axes offset and askew to each other and which cooperate to advance thread in a helical manner. Such two-element reels, usually, have been adapted for the performance of a single processing step. Because of their adaptability in a continuous process it would be advantageous to perform a plurality of processing steps on them.

A reel has been proposed by the Lovett Patent 2,167,662 which permits the performance of more than one thread processing step. The patent discloses a reel having at least two eccentric reel member sections in lieu of one continuous eccentric reel member. The one reel member was replaced by the two to lengthen the reel and to overcome possible bar interference between adjacent bar members which would result if the bar members of such an eccentric reel member would exceed a length being dependent upon the amount of askewness, the spacing between the bar members, and the number of bar members used. Lovett's solution to overcome bar member interference was to position the eccentric reel members in the same direction, and inclining each about the same amount, generally in the same plane.

While such a stepped or substantially saw-tooth positioning of the eccentric reel members advances thread over the reel, the thread helix is somewhat distorted upon being transferred from one reel member section to another. The distortion of the helix tends to impair the quality of the thread as well as to reduce, to an extent, the effectiveness of certain treatments because of a change in the pitch of the turns of thread.

This invention advantageously provides for a manner of arranging a plurality of eccentric reel sections in a reel which permits the thread helix to travel over the reel from one section to the next succeeding section with a minimum of distortion and also with a minimum of change in the pitch of the helix. The reel sections com-

2

prise a plurality of eccentric reel members that are positioned in a manner so that their axes intersect. Further, the bar members of the reel sections are tapered at the contiguous portions, both in vertical and horizontal planes to minimize thread transfer difficulties. The bar ends of one reel can, also, be indented and the ends of the complementary bars can extend thereto. All of the bar transfer points in the contiguous portions and the point of eccentric axis intersection lie, generally, in the same plane, that is in a plane that is substantially vertical to the reel supporting shaft or the axis of the concentric reel member.

Such an improved reel, further, advantageously lends itself to the performance of a plurality of processing steps, each processing step being performed on a separate reel member section. Thus, where the Lovett reel advances thread or the like in a series of somewhat abrupt lengths determined by the reel sections, the reel of this invention advantageously advances the thread in a substantially smooth manner eliminating the periodic offsetting thread transferring steps.

Such an advantageous manner of positioning the plurality of eccentrically positioned reel members permits the construction of a reel that can be of any length desired. The reel can be utilized to perform a plurality of processing steps on the thread traveling thereover, making each processing an individual one. The reel of this invention will be better understood from the following description and accompanying drawing, where:

Figure 1 is a plan view of the reel;

Figure 2 is a cross section of the reel showing the advantageous positioning of the reel members;

Figure 3 is an end elevation of the reel of Figure 2;

Figure 4 represents a serrated locking means utilized to lock the offset and askew reel members in position;

Figure 5 is a schematic diagram showing the advantageous position of the axes of the respective reel members comprising the reel; and

Figure 6 represents a modification in construction of the transfer portion of the bar members.

Referring to the drawing the reel comprises a concentrically mounted reel member 10 and at least two reel members 11, 12 that are offset and askew to the concentric reel member. All of the reel members have peripheries of a plurality of longitudinally extending bar members.

One plurality of bar members 13 forms the

periphery of the concentric reel member 10. The bar members 13 extend unbrokenly for their entire length ending desirably in a supporting ring 14 at one end and in a flange 15 at the other end. The supporting ring 14 is concentrically mounted on a shaft 16 to which it is fixed by means of a set screw 17 which is threaded in a hub portion 18 that forms an extension of the supporting ring 14. Desirably the flange 15 is secured by a plurality of screws 20 to a circular supporting member 21 which is concentrically mounted about the shaft 16. The reel member 10 thus has a discontinuous circular periphery that is positioned concentrically about the shaft 16.

In-between the bar members 13 of the concentric reel member 10 there are positioned a plurality of bar members 23, 24 in an end-to-end relation to form separate reel members 11, 12 respectively. The combined lengths of the bars 23 and 24 are substantially equal to the length of the bars 13 of reel member 10. Each set of bar members 23, 24 is supported on a hub that is adapted to rotate about an axis that is offset and askew to the axis of the concentric reel member 10. Advantageously, bar members 23, 24 rotate about axes that are arranged about the axis of the concentric reel member 10 in an end-to-end relation and at askew angles thereto so that they intersect. The eccentrically positioned axes are offset and each lies in a separate plane that is parallel to the axis of the reel shaft and arranged in consecutive order about the reel shaft axis. As shown, bar members 23 are supported by the hub 26 which is rotatably mounted on a sleeve bearing 27 that is positioned about the eccentric 28 carried by a longitudinal bearing sleeve 30 in which rotates the shaft 16. Bars 24 are likewise supported by a hub 32 that rotates about a sleeve bearing 33 mounted on an eccentric 34 also on the sleeve 30. The eccentrics 28 and 34 are offset and askew to the shaft 16. The hubs 26 and 32 are fixed against lateral displacement by an end retaining means such as a washer 36 and a retaining ring 37.

The eccentrics 28 and 34 as hereinbefore mentioned are fixed to the sleeve 30 through which rotates the shaft 16. Sleeve 30 extends through the reel supporting sleeve 40. The reel support 40 has a flared section 41 that is adapted to fit into a position provided for it in a spinning machine (not shown). There is a sleeve bearing 42 on the support 40. The circular supporting member 21 of reel member 10 is adapted to rotate about this bearing.

Advantageously the ends of the eccentrics 28 and 34 are serrated so as to match the serrations of spacer collar 45 as shown in Figure 4. When two serrated ends are abutted such serrations prevent their rotation. Desirably, then, the inner end of the support also is serrated as well as both ends of the eccentric 34, both ends of a spacer 45, and one end of the eccentric 28. The serrations not only prevent rotation of the eccentrics when their position has been determined but they also permit a very fine adjustment of them.

The eccentric reel member assembly is kept from lateral displacement by a collar 46 which abuts against the eccentric 28. The collar has threaded through it a set screw 47 which bears against the reel shaft 16. The concentric member is held in position at one end by a shoulder 49 on the support 40 and at the other end by the set screw 17 in the hub 18. The support 40 itself

abuts a flange 50 on sleeve 30 which in turn abuts an annular ring 51 on the shaft 16.

Further, the reel shaft 16 extends beyond the flanged portion 41 of the support 40. There is mounted at substantially the end of the shaft 16 a driving gear 52. The driving gear 52 in turn incorporates a slip-clutch 53. The clutch 53 comprises a plurality of spring backed balls 55 which are set in recesses provided for them in the annular wall 56 of the gear 52. Springs 57 are seated in radial holes 58 provided for them in a sleeve 59 which is fixed to the shaft 16 by means of a set screw 60. As a result of the clutch, any overload on the reel will not damage the device but will make the gear 52 slip about the sleeve 59.

There is schematically shown in Figure 5 the advantageous arrangement of the axes of the eccentrically rotating reel members. The line A—A represents the axis of the concentric member 10 while the lines B—B and B'—B' represent the axes of the eccentric reel members 12 and 11 respectively. The lines B—B, B'—B' are inclined so that they intersect at a point BB'. This point when radially extended is equivalent to the transition points in the tapered sections of the bar members. Because of being tapered the bars have substantially similar transition points and the thread readily passes from the one eccentric set of bar members to another.

The ends can be desirably tapered or arranged as shown in Figure 6 so that the transition point of each pair of tapered ends is the same and all points lie in about the same vertical plane. The inclination of the axes as shown in Figure 5 is exaggerated in order to emphasize their advantageous arrangement. Actually the inclination is of a very small degree, being only great enough to give the desired rate of travel and a minimum of thread helix distortion over the transition points.

The invention has been described with reference to a two-stage reel although, obviously, the construction lends itself to a reel having as many stages as desired. This can be readily seen from Figure 5 where there is shown an additional axis B''—B''.

I claim:

1. A thread advancing reel comprising, a shaft, a reel member concentrically positioned about said shaft having a plurality of longitudinally extending bar members, and a plurality of reel members having longitudinally extending bar members also positioned about said shaft on axes arranged in an end-to-end relation about the axis of said shaft each at an angle to said shaft axis so that they intersect, said plurality of reel members being disposed in an end-to-end relation on the intersecting axes and their bar members being in an alternate relation with the bar members of said concentrically positioned reel member.

2. A thread advancing reel comprising, a shaft, a reel member concentrically positioned about said shaft having a plurality of longitudinally extending bar members, and a plurality of reel members having longitudinally extending bar members also positioned about said shaft on axes that are offset and arranged in an end-to-end relation about the axis of said shaft each at an angle to the shaft axis so that they intersect, said plurality of reel members being disposed in an end-to-end relation on the intersecting axes and their bar members being in an alternate relation with the bar members of said concentrically positioned reel member.

3. A thread advancing reel comprising, a shaft, a reel member concentrically positioned about said shaft having a plurality of longitudinally extending bar members, and a plurality of reel members having longitudinally extending bar members also positioned about said shaft on intersecting axes that are offset and askew to the axis of said shaft and arranged about said shaft in an end-to-end relation, said plurality of reel members being disposed in an end-to-end relation with the ends of bar members of one reel member being contiguous with the ends of the bar members of the next succeeding reel member and all bar members of said plurality of reel members being in an alternate relation with the bar members of said concentrically positioned reel member.

4. A thread advancing reel comprising, a shaft, a reel member concentrically positioned on said shaft having a plurality of longitudinally extending bar members, a plurality of reel members also positioned about said shaft and rotating on axes

5 that are offset and askew thereto and arranged in an end-to-end relation about the axis of said shaft, said axes of said plurality of reel members being positioned about the shaft axis at an angle so that each intersects the other, the bar members of said plurality of reel members being in an end-to-end relation and alternately disposed with the bar members of said first reel member, and said ends of the bar members of said plurality of reel members at their end-to-end portions being configured to provide for continuity of thread supporting surface.
